GAS OR VAPOR FILLED DISCHARGE TUBE

Alfred Pützer, Berlin-Spandau, Germany, assignor to Siemens & Halske Aktiengesellschaft Siemensstadt, near Berlin, Germany, a corporation of Germany

Application October 27, 1937, Serial No. 171,329
In Germany October 1, 1936

2 Claims. (Cl. 250—27.5)

The invention relates to an electrical discharge device and especially one with a plurality of anodes.

An object of the invention is to prevent undesired discharges between electrodes in a device having a plurality of current paths therein.

In devices having a plurality of current paths, such as the tubes having a plurality of anodes, and possibly a plurality of auxiliary electrodes, with a common cathode, there is a comparatively great danger of undesired discharges.

These discharges may be either a backfire or a forward-fire to an electrode in another current path than that desired. The safety protection against this undesirable ignition phenomena is not sufficient as it should be in tubes of this type of the prior art, unless the tubes are constructed with a comparatively complicated structure.

The construction of such discharge tubes is rendered more difficult because of the stresses which arise as a result of the utilization of high power and by the requirement that distances between electrodes be accurately maintained.

An object of the present invention is a discharge device which combines great operating safety and simple mechanical construction.

Other objects and advantages of the invention will be apparent from the following description and drawing in which Figure 1 is a top cross-sectional view of electrode structure embodying the invention. Fig. 2 is a perspective view of the device similar to Fig. 1 with parts broken away and the curved parts elliptical instead of cylindrical; and Figs. 3, 4, 5, 6 and 7 are top cross-sectional views illustrating various modifications of Fig. 1.

Fig. 1 shows schematically the structure of a two-anode grid control discharge device according to the invention. The cathode 1 is preferably centrally placed therein. This cathode is preferably of the hot cathode type and constructed as a spiral. In this construction the auxiliary electrode 3 is preferably utilized as a cylindrical grid, which is common for the two current paths described in the device. The grid has preferably slots 5 on two opposite sides of the cathode for the penetration of the discharge to the anodes. This control electrode 3 has the flange shaped projection 4 extending therefrom preferably in a line at right angles to the alignment of the two slots 5. The anode structure is disclosed as comprising two curved members 2 forming semi-cylindrical sheet members having flanges 6 extending therefrom. The flanges 6 of the two anodes 2 are fastened on the flange

shaped protecting surfaces for the grid electrode with the interpositioning of intermediate layers of insulating material 8. The discharge spaces extending from the common cathode 1 to the two anodes are separated from each other by the aforementioned projecting surfaces 4. The whole system is preferably enclosed by a metallic screen 7.

In Fig. 2 is perspectively illustrated the elements mentioned in connection with Fig. 1 except that the parts 2, 3 and 7 are elliptical in cross-section. This assembly may be placed in any suitable glass or other type container which will be filled with a metallic vapor or noble gas. This figure illustrates the preferred structure of the metallic screen 7 which has two covers 9 and 11 for the ends of portion 7. The upper cover 11 is preferably constructed as a network in order that the structure may be properly pumped out preparatory to the introduction of the desired gas or vapor into the discharge valve. The electrode system is connected by current conducting leads extending through small insulating tubes 10 from the usual press through the bottom plate 9. The current conducting lead 13 to the cathode preferably passes through the plate 9 and the return of the heat current is preferably through the upper cover 11 and the metal screen 7 to the wire 14.

As illustrated in these two figures the anodes of the discharge device form a unit enclosing a cathode and these anodes are electrically separated from each other by longitudinal joints with insulation inserts. The anodes and control electrodes are of cylindrical contour although other curved or straight-sided sheet material may be utilized. These anodes and control electrodes form a mutually supporting unit with fixed distances maintained between the elements. The distances of the screen 7 from the electrode surface as well as the covers of the screen are preferably that of the mean free path of an electron of the gaseous medium of the discharge device. The discharge between the exterior surfaces of the anodes are thus avoided and undesirable discharges between the interior surfaces or the anodes are prevented by the separation provided by the control electrode. The protective cylinder offers in addition the further advantages that by reason of its presence, disturbances because of wall charges, are avoided.

The mechanical connection of the individual cylinder parts forming the anodes preferably takes place by means of flanges arranging longitudinally of the anodes and by the insertion 55

of intermediate layers of insulating material. The radial projection surfaces of the control electrode or electrodes are preferably so constructed that they penetrate between the flanges forming 5 the connection between the two anodes and are held rigidly insulated therebetween. The flange connection is preferably carried out by insulating screw coupling.

Under certain circumstances the flange shaped 10 projection of the auxiliary electrode may be projected between the flanges of the anodes to the outer cylindrical screen either with or without the insertion of insulating material between the auxiliary electrode and the screen. These flange 15 shaped projections from the auxiliary electrode to the outer screen are illustrated in Fig. 3. The inserts of insulating material may be superfluous when no control effect is to be exerted and only a separation of the discharge spaces and possibly 20 a partial screen of the cathode is desired as for example in rectifier tubes. The flange projections are in that case brought through the anodes by insulation and are fastened directly to the outer cylindrical metallic screen. This arrangement 25 is particularly for use when a suitable potential, for example, cathode potential, is to be applied to the metallic screen. In Fig. 3 the electrode 3 would serve not for control purposes, but together with those projecting surfaces full- 30 fill the task of separating the discharge spaces and of screening the cathode. The projecting parts 4 are both insulated from the anode 2 but are fastened to the screen 7 directly so that they together with the electrode part 3 take on the 35 potential of the cathode terminal.

Fig. 4 shows the invention applied as a 3-phase rectifier. The anode structure comprises three separate insulated anodes 2. In this case the openings in the auxiliary electrodes, which may 40 be used for screening or control, are arranged in a manner corresponding in direction with the anode with which they cooperate.

Fig. 5 discloses 3-phase discharge device with a common grid which basically corresponds in its structural features to the rectifier according 45 to Fig. 3.

In Fig. 6 a 3-phase control vessel with separate grids differs from that illustrated in Fig. 5 by the insulating intermediate layers 12 between the projecting parts 4 of the control electrodes. 50

Fig. 7 discloses the invention as applied to a discharge device that is especially adapted to be

an inverter with two anodes. In this case the grid electrodes are again separated from each other by insulation 15 while the remainder of the construction corresponds to the discharge device illustrated in Fig. 1.

The arrangement of the electrode system as described not only has the advantage of a complete protection against undesired discharges but also there is a high resistance against all mechanical and thermic stresses. The mutual support of the anodes and auxiliary electrodes maintain the electrode distances completely constant and this is of great importance in maintaining the tube characteristics constant. Either or both the auxiliary electrode and anode current leads 15 or the tubes 10 are made sufficiently rigid to support the structure.

It is clear that this simple construction offers many application possibilities in particular as regards the number and arrangement and functioning of the electrodes. Thus it is possible to construct the tube as a full-wave rectifier, a full-wave valve or a 3-phase valve, etc. By proper arrangement of the insulation it is possible to maintain the control electrodes influencing the 20 individual discharge paths either separate or common. From this possibility a number of structural forms may evolve of which the forms described on the drawing are only examples. Accordingly, it is desired that only such limitations 25 be imposed on the following claims as are necessitated by the prior art.

I claim as my invention:

1. An electrical discharge device comprising a cathode and a plurality of anodes and control electrodes, said control electrodes cooperating to form an enclosure about said cathode and having solid insulating means between the various control electrodes, and said anodes cooperating to form an enclosure about said cathode and control electrodes and having insulation means between the various anodes.

2. An electrical device comprising a cathode, a plurality of curved conductive members enclosing said cathode and having openings therein, a plurality of flanges from said members, a plurality of curved conductive members enclosing said cathode and said first curved conductive members and insulating means joining said last mentioned curved members to the flanges on said 40 first mentioned curved members.

ALFRED PÜTZER.
